TRUCK

Verner E. Bergman, 4042 Wanamaker Road,
Topeka, Kans. 66610

Filed Dec. 4, 1970, Ser. No. 26,286

Term of patent 14 years

Int. Cl. D12—08

U.S. Cl. D14—3

FIG. 1 is a side elevational view of the truck embodying my new design, the side opposite being identical in appearance to that shown in FIG. 1;

FIG. 2 is a front elevational view thereof;

FIG. 3 is a rear elevational view thereof; and

FIG. 4 is a top plan view thereof.

I claim:

The ornamental design for a truck, as shown and described.
